AUTOGRAPHIC REGISTER

William C. Pfeiffer, Dayton, Ohio, assignor to
The Egry Register Company, Dayton, Ohio, a
corporation of Ohio

Application August 18, 1937, Serial No. 159,743

5 Claims. (Cl. 282—12)

This invention relates to autographic registers, and in particular, to portable autographic registers having mechanisms for causing predetermined lengths of record sheets to be presented for detachment after the writing operation has been completed.

One object of this invention is to provide an autographic register employing zigzag folded webs in connection with an aligning member which engages the folds, and a pressure member which normally urges the fold into an acute angle around the aligning member, but which is connected to mechanism causing it to be urged rearwardly to convert the acute angle into an obtuse angle and release the webs for withdrawal.

Another object is to provide an autographic register having zigzag folded webs employed in connection with an aligning edge associated with a writing table, together with mechanism for selectively altering the normally acute angle of the zigzag folded strip to an obtuse angle at the aligning member so as to release the web from locking engagement and allow it to pass easily around the aligning member during the withdrawal operation.

Another object is to provide an autographic register with the previously described mechanism, wherein the web passes between a movable member and a yieldingly urged member for engaging the webs to change the acute angle to an obtuse angle, and facilitate the passage of the webs around the aligning edge, this mechanism being preferably operated by a manually actuated member adjacent the tear-off edge of the web.

Cross reference is hereby made to the copending application of Clayton E. Wyrick, Ser. No. 142,662, filed May 14, 1937, assigned to the same assignee and containing certain broader claims than the claims herein presented.

In the drawings:

Figure 1 is a top plan view of one embodiment of the autographic register of this invention.

Figure 2 is a top plan view, similar to Figure 1, but with the cover removed in order to disclose more completely the mechanism beneath the cover.

Figure 3 is a side elevation of the register shown in Figure 1.

Figure 4 is a side elevation, similar to Figure 3, but with the cover raised to show the mechanism within.

Figure 5 is a vertical section along the line 5—5 in Figure 1, with the web in its acute angle locked position.

Figure 6 is a view similar to Figure 5, but with the mechanism shifted to convert the acute angle of the web into an obtuse angle for passage around the aligning edge.

Figure 7 is a cross section along the line 7—7 in Figure 5.

Figure 8 is a fragmentary top plan view of the rearward end of the register shown in Figure 2, but with the mechanism in the position shown in Figure 5, in section along the line 8—8 thereof.

Figures 9 and 10 are fragmentary enlarged sections of modifications of the corresponding portions of Figures 5 and 6.

Figure 11 is a left-hand side elevation of the modified mechanism shown in Figures 9 and 10, looking in the direction of the line 11—11 in Figure 9.

General construction

In general, the autographic register of this invention consists of a casing having a writing table and a compartment for zigzag folded webs. Associated with the writing table is an aligning member, such as a straight edge, for engaging the folds in the webs so as to lock the webs in a fixed position because of the normal inability of the acute angle of each web to pass by a straight edge inserted therein. Associated with the aligning member or straight edge is a releasing device, and a yieldingly urged member between which the webs pass. The releasing device is operated manually to alter the acute angle of the web to an obtuse angle in order to facilitate its passage around the aligning member or straight edge. The web may then be withdrawn from the register by grasping it between the fingers, but when a predetermined length has been withdrawn another acute-angled folded portion in the web reaches and engages the aligning member or straight edge. The fold of the web thereby locks itself against the straight edge because by this time the releasing member has been withdrawn and the yieldingly urged member is now engaging the web to one side of the aligning member or straight edge. The yieldingly urged member may consist of a flexible strip, such as a flat spring, or it may consist of a finger urged against the web by a spring.

Casing construction

The autographic register casing assembly consists of a base plate 10 (Figures 5 to 8), having supporting feet 11 secured thereto for supporting the base plate upon a table or counter. Rising from the base plate 10 are side walls 12 and 13.

on the right and left-hand sides of the assembly. Arranged between the side walls 12 and 13 and spaced above the base plate 11, is a floor plate 14 (Figure 7) upon which the stacked webs are placed in zigzag folded form. The forward end of the floor plate 14 is bent in three directions. The midportion 15 is bent upwardly substantially at right angles so as to form an end positioning member for the web pack, whereas the portions 16, on opposite sides of the portion 15, are bent at angles thereto so as to form members for guiding detached web portions into the storage compartment 17, located in the space between the floor plate 14 and the base plate 10. The rearward edge of the floor plate 14 is bent downwardly, as at 18, to form a rear wall for the storage compartment, the side walls of which are formed by the side walls 12 and 13 of the casing assembly.

20 Journalled in the side walls 12 and 13 are the pivot rods 21 which support the opposite sides 22 and 23 of the casing cover, generally designated 24. Also pivotally mounted upon the inner ends of the pivot rods 21 are the bent arms 25 (Figure 6), the forward ends of which support a movable closure 26 for a slot 27 in the forward wall of the casing cover 24. The motion of the casing cover 24 is limited by a pair of slotted arms 28 pivoted, as at 29, to the side walls 30 of the casing cover 30 and having slots 31 engaging the grooved ends 32 of a rod 33 secured to the side walls 12 and 13 of the casing assembly (Figure 4).

Pivotedly mounted upon the pins 34 on the side walls 12 and 13 are the downwardly directed flanges 35 of the writing table 36 (Figure 7). The forward end of this writing table is depressed, as at 37, to form a space wherein the forward ends of the webs can be conveniently grasped between the fingers of the operator. Secured to the under side of the writing table 36 are bent spring fingers 38 which pass upwardly through slots 39 in the top thereof, emerging immediately above the depressed portion 37. These spring fingers engage the under side of the webs and tend to push them upward so as to make grasping more convenient. The rearward ends of the writing table 36 are provided with tabs 40, which come to rest in hollow posts 41, secured to the side walls 12 and 13 (Figure 5). The tabs 40 and posts 41 cooperate to position the writing table 36 when it is lowered to the writing position. The writing table 36 may be raised around its pivot pins 34 by lifting the rearward end thereof. With the writing table 36 in its raised position, the zigzag folded web packs may be more easily inserted into the space immediately above the floor plate 14.

Secured to the left-hand side of the casing assembly and mounted upon the side wall 13 are brackets 42 and 43, respectively. The bracket 42 is provided with a hole 44 and the bracket 43 with a slot 45 for the reception of the supporting shaft 46 of a carbon roll 47. A spring 48 (Figure 2) and a sliding washer 49 cause the carbon roll 47 to be firmly held in its brackets 42 and 43. The carbon roll 47 carries rolled up webs 51 of manifolding material. The individual manifolding or copying webs 51 are interleaved between the individual record webs 52 having the printed forms thereon. The free ends of the manifolding webs 51 are firmly held in position against the side wall 12 by means of a carbon-retaining bar 53 which is pivoted, as at 54, to the side wall 12 and provided with a U-shaped slot 55 at its opposite end engaging a stud 56 secured to the side

wall 12 (Figures 4 and 7). The carbon-retaining bar 53 is provided with projections 57 which yieldingly engage depressions or holes in the side wall 12 (Figure 4), thereby releasably retaining the bar 53 in its carbon-clamping position.

Secured to the rearward end of the casing cover 24 is a spring 58, having a releasing button 60. The end of this spring 58 engages a locking slot 63 in the bottom wall 10 of the casing, and is released therefrom by pressing the button 60. The opening and closing of the closure 26 at the forward end of the casing is similarly regulated by a button 62, connected to latch mechanism (not shown) and forming no part of the present invention. The closure 26 is urged into an open position by springs (not shown) when the button 62 is depressed and the latch mechanism moved into its releasing position. The free ends of the spring arms 38 are engaged by arms 63 (Figures 5 and 6) mounted upon the rod 33 (Figure 2), the outer end of which carries an arm 64 provided with a projection 65 at its free end. Projections 66 and 67 serve as stops for limiting the motion of the arm 64. Consequently, when the arm 64 is moved forwardly the associated arms 63 depress the outer ends of the spring arms 38 and release the webs 52 from engagement with the corrugated rollers 90.

The cover 24 is provided with an aperture 74 (Figure 1) which discloses the writing space upon the individual webs 52. Above the forward part 75 of this aperture 74 is mounted a bridge member 76 secured at its opposite ends to the cover 24. Secured, as at 77, to the under side of the cover 24 immediately beneath the rearward edge of the aperture 74, is a spring finger 78, the free end of which is bent downwardly so as to yieldingly engage the webs 52 and urge them into contact with the writing table 36 immediately adjacent its rear edge 79 (Figure 5). The rearward edge 79 of the writing table 36 also serves as an aligning member for the webs 52 by engaging the folds between successive webs, as will be described hereinafter in detail. The forward edge of the bridge member 76 on the cover 24 is cut away, as at 80, to permit the free motion of a handle 81 which is moved to and fro by the operator during the operation of the autographic register.

For this purpose the handle 81 consists of an upwardly extending portion, the lower part 82 of which (Figure 5) is mounted upon the cross bar 83 having downwardly bent ends 84 pivotally supported upon the pins 85 for swinging movement (Figure 6). The cross bar 83 is extended rearwardly, as at 86, and above it is mounted a curved shield plate 87 secured to the handle 81 and adapted to cover the space beneath the cutaway portion 80 in the bridge member 76. The bridge member 76 is provided with a slot 88 to permit the passage of the shield plate 87 therethrough when the handle 81 is moved rearwardly (Figure 6). Mounted in slots 89 in the cross bar 83 are two corrugated rollers 90. These rollers are arranged immediately above the spring fingers 38 and engage the uppermost surface of the webs 52, the lowermost surface of which is engaged by the spring fingers 38. When the handle 81 is moved rearwardly (Figure 6) the corrugated rollers 90 rotate as they move rearwardly over the uppermost surface of the webs 52, and at the same time the forward ends of the spring fingers 38 are permitted to rise by reason of their having been freed from engagement with 75

the rollers 90. This action pushes up the forward edges of the webs 52 and positions them more conveniently for grasping by the operator, who inserts his fingers in the depressed portion 37 for this purpose. The cover is releasably held in its closed position by the engagement of a spring latch 59 (Figure 5), operated by a button 60 and engaging the slot 93 in the base plate 10.

10 Aligning mechanism

The aligning mechanism is operated by the handle 81 and the portions 84 of the swinging cross bar 83. For this purpose a stud 94 (Figures 2 and 4) is mounted upon one of the portions 84 and serves not only as an anchorage for one end of a coil spring 95, the opposite end of which is anchored as at 96 to the side wall 12, but also engages a slot 97 in a reciprocating bar 98. The reciprocating bar 98 is pivotally mounted at its opposite end on a stud 99, and retained in position by a spring 100. The stud 99 is mounted upon one of a pair of swinging arms 101, the upper ends of which are interconnected by the cross member 102, and the lower ends of which are pivotally supported upon the pivot rod 103. The pivot rod 103 is mounted upon the upwardly extending ends 104 of a bracket 105 (Figure 5) mounted upon the base plate 10. Immediately adjacent the cross member 102 and 20 mounted between the arms 101 is a rotatable roller 106.

The purpose of the roller 106 is to change the normally acute angle between the adjacent sections of the webs 52 to an obtuse angle, as shown in Figure 6, and thereby to enable the folds 111 of the webs 52 to move around the aligning edge 79 without locking thereagainst. When the roller 106 is in its forward position (Figure 5), however, it no longer engages the webs 52 and their folds 111 again become acute angles, thereby locking themselves firmly against the aligning edge 79 of the writing table 36. The roller 106 and its swinging arms 101 are moved to this fold-releasing position when the handle 81 is moved rearwardly, thereby causing the stud 94 to engage the rearward ends of the slot 97 and move the reciprocating bar 98 rearwardly, thereby swinging the stud 99 on the swinging arm 101 likewise rearwardly.

Cooperating with the roller 106 and anchored beneath the pivot rod 103 is a resilient member 112. The upper portion 113 of this resilient member is bent and engages the paper webs 52 immediately beneath the folds 111 and aligning edge 79, whereas the lower portion 114 is likewise bent around the pivot rod 103 with its end 115 resting against the bottom wall 10 of the casing (Figures 5, 6 and 8). The resilient member may consist of a single piece of flexible metal, such as flat spring steel, or it may consist of the modification shown in Figures 9, 10 and 11. In this modification the contact portion 116 consists of a comparatively rigid member having a curved upper end 117, and having bifurcated lower portions 118 bent around the pivot rod 103 so as to find bearing support thereon. The bifurcated portions 118 are separated by a slot 119 exposing a portion of the pivot rod 103, and around which is coiled a coil spring 120 having one end engaging the contact portion 116 and the other end engaging the bottom wall 10 of the register.

Operation

In the operation of the autographic register 75 of this invention, the zigzag folded pack of webs

52 is loaded into the space above the floor plate 14 by lifting the edge 79 of the writing table 36. The free ends of the webs 52 are threaded around the roller 106, and a fold 111 thereof placed adjacent the aligning edge 79. So long as the roller 106 is in its forward position, as shown in Figure 5, the fold 111 forms the apex of an acute angle and consequently the webs 52 are locked firmly in position and aligned properly thereby. The forward free ends of the webs 52 are threaded through the space between the spring fingers 38 and the knurled rollers 90, and emerge beneath the cross bar 83 which serves, in part, as a tearing edge. The parts are now in the position of Figure 5.

10 It is assumed that the operator has previously threaded the manifolding webs 51 into their proper positions between the record webs 52, and secured the free ends of the manifolding webs 51 in position by the bar 53. The operator now 15 enters his record upon the uppermost web 52, this being preferably provided with a printed form for convenience. The records are duplicated upon the underlying webs 52 by means of the manifolding webs 51, and an entry of the entire 20 transaction produced in as many copies as it is 25 convenient to make.

The operator now grasps the handle 81 and moves it rearwardly into the cutaway portion 80 of the bridge member 76, thereby exposing the 30 free edges of the record webs 52. The latter are pushed upwardly by the spring fingers 38 as soon as the ends thereof have been released from engagement with the rollers 90, mounted on the cross bar 83 (Figure 8). The operator then 35 inserts his fingers into the depressed portion 37 and grasps the record webs 52, withdrawing them from the register by a forward motion. Meanwhile, the downwardly-bent portions 84 of the cross bar 83 cause the stud 94 and the reciprocating bar 98 to move rearwardly, likewise moving the swinging arms 101 and the fold-releasing roller 106 rearwardly into the fold-releasing 40 position shown in Figure 6.

When this occurs the top 113 of the resilient 45 member 112 is forced rearwardly from its engagement with the webs 52. With the roller 106 and the resilient member 112 in this rearward position, the webs may be withdrawn by the operator. At the start of the withdrawing operation the 50 fold 111 is immediately converted from an acute angle to an obtuse angle and passes easily around the aligning edge 79 by reason of the fact that the roller 106 is now positioned rearwardly of the aligning edge 79 (Figure 6). When the operator 55 releases the handle 81 the latter moves to its forward position, carrying with it the roller 106 and permitting the resilient member 12 to assume its forward position, shown in Figure 5.

The operator may now detach the written portions of the webs 52 by tearing them at the fold 60 111, which is now adjacent the forward edge of the cross bar 83. The latter serves as a tearing edge, and the folds 111 are preferably indented, perforated or otherwise weakened to assist this 65 action. The operator may now press the button 62 and open the closure 26 to insert a duplicate record into the storage compartment 17. The other copies of the written record may be disposed of in the customary manner, one being 70 given to the purchaser and others being sent to the bookkeeping or other departments concerned with the transaction.

In the operation of the device, the arm 64 is 75 swung manually by the operator by means of

the pin 65, in order to facilitate the threading of the webs through the register. This action depresses the ends of the spring fingers 38, which when released assist in holding the webs taut during the writing operation. The spring fingers 38 create a spring pressure which also urges the cutter bar to return to its position in response to the pull of the web against it when the printed form is withdrawn and detached.

10 It will be understood that I desire to comprehend within my invention such modifications as come within the scope of the claims and the invention.

Having thus fully described my invention, what 15 I claim as new and desire to secure by Letters Patent, is:

1. In an autographic register having a casing for a zigzag folded record web, said register having a platen provided with a fold engaging edge over which the web may be drawn to writing position, a freely pivoted member mounted in a casing and having a rounded end extending away from the web, and spring means for urging said end into engagement with said web and toward 25 said fold engaging edge whereby to cause said web to assume an acute angle against said edge, and web unfolding means for engaging the opposite side of said web, actuating means for moving said web unfolding means to web unfolding position, and for moving said member away from said edge.

2. In an autographic register having a casing for a zigzag folded record web, said register having a platen provided with a fold engaging edge over which the web may be drawn to writing position, a freely pivoted member mounted in a casing and having a rounded end extending away from the web, and spring means for urging said end into engagement with said web and toward 35 said fold engaging edge whereby to cause said web to assume an acute angle against the edge, and web unfolding means comprising a roller for engaging the opposite side of said web, actuating means for moving said web unfolding means to web unfolding position, and for moving said member away from said edge.

3. In an autographic register having a casing

for a zigzag folded record web, said register having a platen provided with a fold engaging edge over which the web may be drawn to writing position, a freely pivoted member mounted in a casing and having a rounded end extending away from the web, and spring means for urging said end into engagement with said web and toward 5 said fold engaging edge whereby to cause said web to assume an acute angle against said edge, and web unfolding means for engaging the opposite side of said web, actuating means for moving said web unfolding means to web unfolding position, and for moving said member away from said edge, said freely pivoted member and said web unfolding means being movable transversely 10 to said fold engaging edge.

4. In an autographic register having a casing for a zigzag folded record web, said register having a platen provided with a fold engaging edge over which the web may be drawn to writing position, a freely pivoted member mounted in a casing and having a bent upper portion extending away from the web, and spring means for urging 20 said end into engagement with said web and toward said fold engaging edge whereby to cause 25 said web to assume an acute angle against said edge, and web unfolding means for engaging the opposite side of said web, actuating means for moving said web unfolding means to web unfolding position, and for moving said member away from said edge.

5. In an autographic register having a casing for a zigzag folded record web, said register having a platen provided with a fold engaging edge over which the web may be drawn to writing 35 position, a freely pivoted member mounted in a casing and having a bent upper portion extending away from the web, and spring means for urging said end into engagement with said web and toward 40 said fold engaging edge whereby to cause said web to assume an acute angle against the edge, and web unfolding means comprising a roller for engaging the opposite side of said web, actuating means for moving said web unfolding means to web unfolding position, and for moving 45 said member away from said edge.

WILLIAM C. PFEIFFER.
